BARREL CONSTRUCTION

Clarence U. Gramelspacher, Jasper, Ind., assignor
to Jasper Wood Crafters, Inc., Jasper, Ind., a
corporation of Indiana

Application October 29, 1945, Serial No. 625,358

2 Claims. (Cl. 217—72)

1

This invention relates to bilge barrels.

An object of the invention is to provide a wooden bilge barrel having a metal lining there-in that is what might be termed a one-piece lining.

Another object of the invention is to provide a bilge barrel constructed from sheets of plywood and having a substantially one-piece metal lining in the barrel.

Still another object of the invention is to provide a wooden bilge barrel, particularly constructed from plywood, wherein the barrel and the metal lining thereof are produced as a unitary article so that the metal lining is disposed within and formed to the contour of the barrel simultaneously with the forming of the barrel.

Still another object of the invention is to provide a wooden bilge barrel wherein the heads of the barrel are retained in position by the contoured form of the barrel and the metal lining positioned therein.

Still another object of the invention is to provide a barrel of the bilge type that is capable of being formed from individual sheets of plywood that are wrapped around a substantially one-piece metal lining and formed to shape around the metal lining, the metal lining also being formed to shape simultaneously with the forming of the barrel.

Further objects and advantages will become apparent from the drawings and the following description.

In the drawings:

Figure 1 is an elevational view of a plywood bilge barrel formed according to the teachings of this invention.

Figure 2 is a vertical cross-sectional view of the barrel illustrated in Figure 1.

Figure 3 is a transverse cross-sectional view of the barrel illustrated in Figure 1.

Figure 4 is an enlarged cross-sectional view showing the barrel and head construction.

Figure 5 is a modified arrangement of bilge barrel incorporating features of this invention.

In this invention the barrel that is the subject matter of invention herein is of the type known as a "bilge barrel," which defines the applicant's barrel, that is, the subject matter of invention, as a round, bulging vessel or cask of greater length than breadth. Barrels, as articles of commerce, are distinguished from cylinders or containers adapted to contain a quantity of material equal to the volumetric content of a barrel in that a barrel is a vessel having bulging sides.

In this invention a wooden barrel is provided

with a metal lining that may be termed a one-piece lining that conforms strictly to the contour of the interior of the barrel to support the metal lining throughout the entire area thereof.

5 Wooden barrels have been particularly desired for many uses because of the strength and resiliency that is obtained in this type of barrel. Particularly, wooden barrels have been preferred to metal barrels in the distilling industry. However, it is well-known that wooden barrels require cleaning and repitching of the interior of the barrels each time they are returned to the distillery for refilling. While the wooden barrel is preferred in this industry, yet the industry 10 has expressed the desire that they would appreciate having a wooden barrel with a metal lining, such as a stainless steel lining, to eliminate the necessity of repitching the barrels after they have been cleansed and sterilized. Also, it is 15 possible to use metal-lined wooden barrels for containing other liquids that would be deleterious to the wood of the barrel, and would avoid all contamination in a liquid contained in a wooden barrel if a metal lining was used therein.

20 25 While the conventional stave-type of barrel is quite strong, yet it has been found that barrels constructed from plywood have a greater strength than conventional stave barrels even though the wall of the barrel is of considerable less thickness than that of the conventional stave barrel. I have previously manufactured and produced plywood barrels in accordance with the method set forth in the Gramelspacher Patent No. 2,365,754 dated December 26, 1944. Therefore, in 30 manufacturing the metal-lined barrel of this invention, the process that is followed in manufacturing the same may be generally the process disclosed in the aforesaid patent, and in accordance with the improvements of that process as set forth in my copending application, Serial 35 No. 625,357, filed October 29, 1945, now Patent No. 2,459,316.

40 In general, the method of manufacturing a plywood barrel according to the method set forth in the Gramelspacher Patent No. 2,365,754 consists of cutting sheets of plywood with substantially V-shaped notches along longitudinal edges thereof. Two or more sheets of plywood are then placed in face to face engagement with adhesive material therebetween with the V-shaped notches 45 of one sheet of plywood laying within the uncut or substantially stave shaped portion of the adjacent sheet of plywood. The assembled sheets of plywood are then rolled into a cylindrical form 50 and inserted into a mold or form having a barrel-

shaped interior. An expandible rubber bag is located within the barrel before being placed in the mold and is then filled with fluid under pressure to force the sheets of plywood outwardly against the interior surface of the barrel-shaped mold, thus forming the side wall of a barrel. Suitable heat is applied to the barrel to cause the adhesive material to bind the adjacent sheets of plywood together.

This general process is improved upon in my copending application, Serial No. 625,857, filed October 29, 1945, in which a thin cylindrical container is used in place of the expandible rubber bag. The metal container in this instance is filled with fluid under pressure and expanded against the plywood to force the plywood to take the barrel-shaped form of the inner surface of the mold. In this instance the metal liner becomes an integral part of the barrel.

The barrel of this invention is, therefore, one that may be formed by the process disclosed in my copending application heretofore referred to and consists of a plurality of individual sheets of plywood 10, 11 and 12 that are provided with V-shaped cuts therein along the longitudinal edges and formed into the shape of a barrel so that the adjacent edges of the cut sections of the plywood sheets will be in abutting relationship as illustrated in Figures 1 and 3. The joints formed by the V-cuts of adjacent sheets of plywood are staggered in the manner illustrated in Figure 3. Before the plywood sheets are formed into the barrel shape a metal container 13 is positioned within the plywood sheets that are wrapped around the container 13.

The heads 14 and 15 of the barrel are then placed within the unformed plywood cylinder and disposed at each end of the metal container 13.

When the metal container 13 is filled with fluid to expand the plywood sheets 10, 11 and 12 outwardly against a barrel-shaped form in the manner disclosed in my copending application heretofore referred to, the metal liner intimately conforms to the interior surface of the barrel during the forming operation thereof and forces the heads 14 and 15 outwardly radially of the barrel. This movement of the heads 14 and 15 causes the periphery of the heads to be urged into the inner plywood sheet 12 as illustrated in Figure 4 whereby the heads are securely held between the inner wall of the barrel 12 and the ends 16 and 17 of the metal liner 13.

The metal liner 13 may be formed of a substantially cylindrical metal body in which the end walls 16 and 17 are flanged inwardly as illustrated in Figure 2. Central closure plates 18 and 19 may be secured to the end wall flanges 16 and 17 by any suitable processing means whereby the joint between the members 18 and 19 and the end wall flanges 16 and 17, respectively, are sealed.

The metal liner 13 may be any suitable liner, such as stainless steel, copper, aluminum or any other metal desired, depending upon the type of liquid or material that is to be carried within the barrel. The metal liner is preferably a relatively thin sheet metal structure, which of its own weight would not withstand any abuse or substantial internal pressure. Hence, the requirement that the metal liner be supported by the barrel throughout the surface area thereof, which support is obtained when the metal liner is expanded against the inner wall of the barrel. A metal liner of only a few thousandths of an inch

thick is, therefore, all that is required for lining the barrel of this invention.

An adhesive material can be placed between the exterior surface of the metal liner and the interior surface of the barrel so that the metal container will be permanently bonded to the inside surface of the barrel after the adhesive has set. The bonding of the liner to the inside surface of the barrel can be occasioned simultaneously with the bonding of the plywood sheets together that make up the body of the barrel.

While the invention has been disclosed and described particularly with regard to a plywood barrel, yet it will be understood that other forms of wooden barrel construction can be used such as the conventional stave construction of a wooden barrel. In this instance the staves of the barrel would be assembled and a metal container placed within the assembled staves before the heads were placed in the ends of the barrel, and subsequently the metal liner could be expanded into intimate contact with the inner surface of the barrel. Such a barrel is illustrated in Figure 5.

Or if the barrel is constructed of plywood, it need not be constructed in the specific manner heretofore disclosed and described, but the barrel would be formed of a single sheet of plywood that is rolled into the form of a cylinder and is formed by a wet process or a steaming process to soften the wood to permit forming the desired barrel shape into the sheet of plywood.

While the construction of the barrel disclosed and described herein constitutes a preferred form of the invention, yet it will be understood that the device is capable of alteration without departing from the spirit of the invention, and that all modifications that fall within the scope of the appended claims are intended to be included herein.

Having thus fully described my invention, what I claim as new and desire to secure by Letters Patent is:

1. A plywood bilge barrel that consists of, a side wall structure comprising a plurality of layers of plywood formed to the bulging shape of a bilge barrel and adhesively secured together, a head positioned in each end of the barrel inwardly of each end thereof in frictional engagement with the inner surface of the side wall of the structure, said heads having a diameter at their outer faces greater than the normal inside diameter of the barrel at the point of contact between the barrel and the edge of the outer face, and a fluid-tight thin-walled sheet metal container in thorough intimate contact with the inner wall of the barrel and said heads, the outer peripheral edge of said heads being embedded in the inner ply only of the barrel and that portion of the barrel beyond the head being converged inwardly whereby the heads are securely held in position.

2. A plywood bilge barrel that consists of, a side wall structure comprising a plurality of layers of plywood formed to the bulging shape of a bilge barrel and adhesively secured together, a head positioned in each end of the barrel inwardly of each end thereof in frictional engagement with the inner surfaces of the side wall of the structure, said heads having a diameter at their outer faces greater than the normal inside diameter of the barrel at the point of contact between the barrel and the edge of the outer face, and a fluid-tight thin-walled sheet metal container in thorough intimate contact with the in-

inner wall of the barrel and said heads and adhesively secured thereto, the outer peripheral edge of said heads being embedded in the inner edge of the barrel and that portion of the barrel beyond the head being converged inwardly whereby the heads are securely held in position. ⁵
